UNITED STATES PATENT OFFICE.

HOWARD E. TROUTMAN, OF CHICAGO, ILLINOIS.

VENTILATOR.

Application filed August 25, 1923. Serial No. 659,377.

This invention relates to ventilators and relates particularly to ventilators of the ejector type designed and adapted for withdrawing foul or heated air from enclosed 5 or dead air compartments or spaces of vehicles, which are operated by currents of air induced by motion of the vehicle to which applied.

The object of the invention is to provide 10 a ventilator for the purpose and of the type specified, which shall be effective in operation, simple in construction and inexpensive to manufacture and install.

To effect the objects of the invention, my 15 improved ventilator comprises the various features, combinations of features and details of construction hereinafter described and claimed.

In the accompanying drawings in which 20 my invention is fully illustrated,

Figure 1 is a perspective view of one form 25 of ventilator embodying my invention and improvements, shown as applied in use to an automobile for ventilating the space at the rear end of the hood between the dashboard, which separates said space from the engine compartment of the hood and the instrument board, showing the ventilator in operative position.

30 Figure 2 is an enlarged sectional, top plan view of the ventilator shown in Fig. 1, the section being taken on the line 2—2 of Fig. 1.

Figure 3 is a side view thereof showing 35 the ventilator open.

Figure 4 is a view similar to Fig. 3 showing the ventilator closed.

Figure 5 is a sectional elevation thereof on the line 5—5 of Fig. 2.

40 Figures 6 and 7 are views substantially similar to Figs. 2 and 3, respectively, illustrating a modified construction.

Figure 8 is an enlarged front view of a 45 modified form of ventilator embodying my invention and improvements, said ventilator being shown as open; and

Figure 9 is a sectional view thereof on the line 9—9 of Fig. 8.

In the drawings, in which, for purposes 50 of clear and definite illustration, I have shown a ventilator embodying my invention and improvements as applied in use for ventilating the enclosed space or compartment of an automobile, formed by the overhanging rear end of the hood, the dashboard 55 which separates said space or compartment

from the engine compartment of the hood and the instrument board, A designates my improved ventilator as a whole, B the space to be ventilated, b the engine hood and b¹, b² the dashboard and instrument board of the vehicle, respectively.

I desire it to be understood, however, that the particular use or application of my improved ventilator herein shown and described, is illustrative only and that I do not desire to limit myself thereto, as the invention admits of a wide range of application and use and it is my desire and intention to cover and protect the invention 65 for all uses and applications for which it is adapted.

Referring now particularly to Figs. 1 to 5 of the drawings, in which I have shown what I now consider to be the preferable 75 embodiment of my invention, the ventilator A consists of a hinged member designated as a whole A¹, comprising a plate 1 supported so as to be movable towards and from an opening 2 formed in the overhanging rear portion b of the hood and adapted to open and close said opening when in raised and lowered positions, respectively, said plate being so proportioned that its edges will overlap the edges of the hood b 80 surrounding said opening 2.

As shown, the plate 1 is supported and is adapted to be opened and closed by means of a bell-crank lever 3 pivoted to lugs 4 formed on hangers 5 secured to the hood b, 90 the plate 1 being secured to the arm 6 of said bell-crank lever and said bell-crank lever being adapted to be turned pivotally to raise and lower said plate by means of a rod 7 pivoted to the arm 8 thereof, said 95 rod 7 extending through a hole 9 formed in the instrument board b² and being adapted to be secured in open position by means of notches 10 formed therein, which are adapted to engage a rib or lug 11 on said instrument board. The rod 7 is so positioned that its projecting rear end will be conveniently accessible for operation by the driver of the vehicle.

I do not, however, desire to limit myself 105 to the particular means shown for supporting and operating the plate 1, as other means suitable for the purpose will readily suggest themselves to others skilled in the art, and my invention contemplates the use of 110 any desired means for supporting and operating said plate.

Formed on the plate 1 are depending front and side walls or flanges designated, respectively, 12 and 13, said walls being loosely fitted to the corresponding sides of the opening 2 and being so proportioned that they will extend below the seat for the plate 1 in all positions of said plate. As shown, also, the depending front wall 12 of the apparatus is bent to form a segment of a cylinder concentric with the pivotal axis of the bell-crank lever 4.

Formed in the depending front wall or flange 12 of the apparatus are holes 14 secured in which, so that their front ends will be substantially flush with the front side of the wall 12, are ejector nozzles 15 which are adapted to discharge through holes or openings 16 formed in the side walls 13 of the hinged member A¹, the holes 14 being somewhat larger than the discharge ends of said ejector nozzles, which preferably terminate a short distance inside of the side walls 13.

In the preferable construction shown, also, the ejector nozzles 15 are tapered, the discharge ends thereof being appreciably smaller than their front or admission ends. Preferably, also, short pipe sections 17 are secured in the holes 16 in the side walls 13, 20 into which the discharge ends of the ejector nozzles 15 extend, said pipe sections 17 being preferably supported substantially concentric with the discharge ends of said ejector nozzles and being correspondingly flared.

With the described construction, it is obvious that when the plate 1 is raised, as shown in Figs. 1, 3 and 5 of the drawings, and the vehicle is traveling at any considerable speed, currents of air will be created through the ejector nozzles 15, the velocity of which will be proportionate to the speed with which the vehicle is traveling and which will be increased at the discharge ends 40 of the ejector nozzles 15 owing to their reduced size. Obviously, also, the currents of air discharged from the ejector nozzles 15 through the pipe sections 17 secured in the holes 16 in the side walls of the movably supported member A¹ of the ventilator will 45 create a suction in said pipe sections which will operate to draw air from the space B of the vehicle and discharge it through said pipe sections 17.

With the construction described, it is also obvious that the ventilator may be rendered inoperative by merely turning the hinged section A¹ pivotally into closed position, as shown in Fig. 4.

As a modification of my invention, I contemplate dispensing with the depending side walls or flanges 13 and the pipe sections 17, and discharging the ejector nozzles 15 directly through the open sides of the hinged section A¹ of the ventilator. With

this construction, the open sides of said hinged sections may be entirely open and unobstructed but, if desired, my invention contemplates securing fine-mesh screens in the open sides of said hinged sections, which will prevent dust and dirt from entering the compartment B when the vehicle is stationary and the ventilator is open.

This modification is shown in Figs. 6 and 7 of the drawings, in which 1¹ designates the hinged plate forming part of the hinged member A², 12¹ the depending front wall or flange secured thereto provided with the admission openings 14¹, 15¹ the thimbles or elbows secured therein and which discharge 80 through the open sides of the hinged section A¹ of the ventilator, in which fine-mesh screens 18 may be secured.

As a further modification of my invention, I contemplate the use of a hinged section A¹ consisting merely of the plate 1 and the depending front wall or flange 12, said depending front wall or flange being entirely closed and the air being withdrawn from the compartment B by the suction 90 created at the open sides of the hinged section of the ventilator by the currents of air blowing across the same when the vehicle is in motion.

This modification is shown in Figs. 8 and 9 of the drawings, in which 1² designates the plate forming part of the hinged section A¹ of the ventilator, and 12² the depending front wall or flange thereof, said wall or flange being entirely closed.

I claim—

1. In a ventilator adapted to induce suction at an exhaust opening of a space to be ventilated, the combination of a movably supported member comprising a cover plate 105 for covering and uncovering said exhaust opening, a wall which depends from said cover plate in close proximity to a side of said exhaust opening provided with an opening, and an ejector nozzle the admission end of which is secured to said depending wall with its admission end in communication with the opening therein and its discharge end directed laterally with respect to its admission end.

2. A ventilator as specified in claim 1, in which the discharge end of the ejector nozzle is contracted.

3. A ventilator as specified in claim 1, in which the ejector nozzle is substantially elbow shaped.

4. In a ventilator adapted to be applied to an exhaust opening of a space to be ventilated, the combination of a movably supported member comprising a cover plate for covering and uncovering said exhaust opening, means for imparting movement to said cover plate to cover and uncover said exhaust opening, and means in association with said cover plate rendered operative by cur-

- rents of air traversing said ventilator, for inducing suction at said exhaust opening, when said cover plate is in open position comprising a wall provided with openings 5 which depends from the cover plate in close proximity to a side of said exhaust opening, side walls provided with discharge openings which also depend from said cover plate into said exhaust opening, ejector nozzles secured 10 to said first-mentioned wall with the admission end of each thereof in communication with an opening therein and the discharge ends thereof directed laterally with respect to their admission ends and in opposite directions to each other, each in line with the discharge opening in a side wall.
5. A ventilator as specified in claim 4, in which the movably supported member also includes pipe sections secured to the side 15 walls thereof in communication with the discharge openings therein, each of the discharge ends of said ejector nozzles being contracted and said pipe sections being outwardly flared.
6. A ventilator as specified in claim 4, in which the movably supported member also includes pipe sections secured to the side walls thereof in communication with the discharge openings therein, and the discharge ends of the ejector nozzles terminate intermediate the ends of said pipe sections. 25
7. A ventilator as specified in claim 4, in which the movably supported member also 30 includes pipe sections secured to the side walls thereof in communication with the discharge openings therein, and the discharge ends of the ejector nozzles terminate intermediate the ends of said pipe sections, the discharge ends of said ejector nozzles being contracted and said pipe sections being outwardly flared. 35

In witness that I claim the foregoing as my invention, I affix my signature this 14th day of August A. D. 1923.

HOWARD E. TROUTMAN.
